[57] CLAIM

The ornamental design for a plant hanger, as shown and described.

DESCRIPTION

FIG. 1 is a front elevational view of the plant hanger of the present invention;

FIG. 2 is a back elevational view of the plant hanger of FIG. 1;

FIG. 3 is a left side elevational view of the plant hanger of FIG. 1;

FIG. 4 is a right side elevational view of the plant hanger of FIG. 1;

FIG. 5 is a top plan view of the plant hanger of FIG. 1; and, FIG. 6 is a bottom plan view of the plant hanger of FIG. 1. The broken lines shown in FIG. 1 are for illustrative purposes only and form no part of the claimed design.
